CLAIM

The ornamental design for a wearable device with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a wearable device with graphical user interface showing the claimed design;
FIG. 2 is a rear view thereof;
FIG. 3 is a left side view thereof;
FIG. 4 is a right side view thereof;
FIG. 5 is a top view thereof;
FIG. 6 is a bottom view thereof; and,
FIG. 7 is a rear perspective view thereof.

(Continued)

The dot-dash broken lines in the figures and the areas within the dot-dash broken lines shown in reduced opacity show portions of the wearable device with graphical user interface that form no part of the claimed design.
